PARTITION BLOCK

Filed Oct. 13, 1930

Samuel Lapof

INVENTOR

BY *Haasbeller*
ATTORNEY

UNITED STATES PATENT OFFICE

SAMUEL LAPOF, OF BROOKLYN, NEW YORK, ASSIGNOR TO BAR-RAY PRODUCTS, INC.,
OF NEW YORK, N. Y., A CORPORATION

PARTITION BLOCK

REISSUED

Application filed October 13, 1930. Serial No. 488,248.

This invention relates to devices impervious to X-rays, and which may be utilized as a protection against the injurious effects of such radiation.

5 Protection against X-rays is a necessity for all persons in proximity to apparatus emitting such rays. Heretofore, protective construction has included the use of lead almost exclusively in complicated, cumbersome, uneconomical and frequently inefficient forms.

10 It is an object of this invention to provide a partition block which is impervious to X-rays, at the same time being economical and of such a shape as to facilitate its handling.

15 A further object is the provision of partition blocks which may be assembled to produce a partition having the usual outward appearance, at the same time being completely impervious to X-rays.

20 These and other objects are attained by the novel construction, combination and arrangement of parts hereinafter described and shown in the accompanying drawing, constituting a material part of this disclosure, and in which

25 Fig. 1 is a perspective view of a partition block embodying the invention.

30 Fig. 2 is an elevational view of a partition or wall formed from blocks embodying the invention.

35 Fig. 3 is a sectional view taken on line 3—3 of Fig. 2.

40 Referring to the drawings, in Fig. 1, the partition block is shown to include a pair of slabs 5, which may be made of gypsum, concrete, or the like. Each slab has a centrally positioned substantially rectangular recess in which is placed a fibrous material 9, such as celotex, or the common types of fiber boards. The slabs are separated by a sheet of lead 7, which is secured to the fibrous material 9 by an adhesive.

45 As shown in Fig. 3, the edges of the sheet of lead 7 project beyond the edges of the slabs

to provide flaps 8, and the edges of the slabs are grooved at 10. By means of this arrangement, a block may be joined to another block by mortar 6, and the flaps 8 of the adjacent blocks overlie each other to provide a continuous lead surface to prevent the passage of X-rays, the grooves 10 allowing the flaps 8 the freedom of movement necessary to such a purpose.

50 A partition may be readily constructed with blocks of the type described to produce a wall of common outward appearance such as shown in Figure 2, which wall is at the same time absolutely impervious to X-rays.

55 Heretofore, lead sheets have been attached to concrete or gypsum by means of projections or loops embedded in the concrete. By means of my invention, such construction of lead sheets is not necessary and by attaching the lead sheets by means of an adhesive the cost of producing the block is materially reduced.

60 The foregoing disclosure is to be regarded as descriptive and illustrative only, and not as restrictive or limitative of the invention, of which obviously an embodiment may be 65 constructed including modifications without departing from the general scope herein indicated and denoted in the appended claims.

70 Having thus described the invention, what is claimed as new and desired to protect by Letters Patent, is:

75 1. A block for use in constructing a wall impervious to X-rays, comprising a pair of slabs of gypsum or concrete, each slab having a central recess in which is positioned a fibrous material, and a lead sheet secured to the fibrous material by adhesive and separating the slabs, the edges of the lead sheet projecting beyond the edges of the block.

80 2. A block for use in constructing a wall impervious to X-rays, comprising a pair of slabs having fibrous material attached to their adjacent faces and a lead sheet separating the slabs, said sheet being attached to

85

90

the fibrous material by means of an adhesive.
3. A block for use in constructing a wall
impervious to X-rays, comprising a pair of
slabs having their adjacent faces bevelled to
form grooves, and a lead sheet, positioned
between and attached to the slabs, the edges
of the sheet projecting beyond the edges of
the slabs.

In testimony whereof he has affixed his
signature this 8th day of October, 1980.

10 SAMUEL LAPOF.
